UNITED STATES PATENT OFFICE.

CHARLES T. McCUE, OF HARTFORD, CONNECTICUT.

DESIGN FOR AN AXLE END.

SPECIFICATION forming part of Design No. 34,379, dated April 16, 1901.

Application filed October 30, 1900. Serial No. 34,954. Term of patent 7 years.

To all whom it may concern:

Be it known that I, CHARLES T. McCUE, a citizen of the United States, residing at Hartford, in the county of Hartford and State of Connecticut, have invented and produced a new and original Design for an Axle End, of which the following is a specification, reference being had to the accompanying drawings, forming part thereof.

Figure 1 is a view in side elevation of an axle end embodying my improvement. Fig. 2 is a top or plan view of the same. Fig. 3 is an end view of the same.

My design relates to that part of an axle located near the outer ends and is embodied in the axle end which forms a distinct article of manufacture.

As shown in the accompanying drawings, the axle end is curved in one direction toward

the center and terminates in a reverse curve 20 at the outer end.

The essential and distinguishing feature of the design resides in the axle-arm *a*, forming the extreme outer end of the axle end, and a projection *b*, extending from the upper surface of the axle, with its axis parallel with the axis of the axle-arm and terminating in a cylindrical portion *c*, having at each end flanges, giving it a spool-form appearance.

Having described my invention, what I 30 claim as new, and desire to secure by Letters Patent, is—

The design for an axle end as herein shown and described.

CHARLES T. McCUE.
